(57) **CLAIM**

The ornamental design for an oxygen concentrator, as shown and described.

DESCRIPTION

FIG. 1 is a perspective view of an oxygen concentrator showing my new design;

FIG. 2 is another perspective view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a perspective view of the oxygen concentrator with its handle in an upright position.
The broken lines depict portions of the oxygen concentrator that form no part of the claimed design.
